UNITED STATES PATENT OFFICE

2,484,568

MAGNETIC RECORDER METHOD AND MEANS

Hugh A. Howell, Valparaiso, Ind., assignor to The Indiana Steel Products Company, Chicago, Ill., a corporation of Indiana

Application October 18, 1946, Serial No. 704,035

3 Claims. (Cl. 179—100.2)

1

This invention relates to a magnetic recorder method and means, and more particularly, to a novel arrangement and method for giving base boost without necessitating any additional base energy input.

One of the particular problems which arises in any magnetic recording lies in the fact that base notes are not normally recorded with as high a relative energy level as are frequencies in the middle and high audio frequency ranges. Various arrangements have been provided for overcoming this shortcoming and have largely involved compensation for the low energy level of the low frequency notes by introducing additional base energy or by decreasing the response of the middle and high frequency ranges through some sort of an equalizer circuit.

One of the principal features and objects of the present invention is to provide a novel method and means for providing base boost without having any more base energy input and without providing an equalizer circuit which will dampen any of the other frequency ranges.

A further object of the present invention is to provide a novel method and means for recording on a record member which includes a non-magnetic base or carrier portion and a magnetizable portion.

Another and further object of the present invention is to provide a novel method and means for recording on a magnetic tape which is formed of a non-magnetic carrier coated with a magnetizable material.

A still further object of the present invention is to provide a novel recording and reproducing arrangement employing a pair of electromagnetic transducer heads disposed on opposite sides of a magnetic record member, the flux field set up in the non-magnetic gap of each of the heads being substantially parallel to the direction of travel of the record member.

The novel features which I believe to be characteristic of my invention are set forth with particularity in the appended claims. My invention itself, however, both as to its organization, manner of construction and method of operation, together with further objects and advantages thereof, may best be understood by reference to the following description, taken in connection with the accompanying drawing, in which:

Figure 1 is a diagrammatic view of a magnetic record member passing between a pair of electromagnetic transducer heads; and

Figure 2 is an enlarged fragmentary view of the pole tip portions of the two heads shown in

2

Figure 1 with the record member passing thereby and in which the flux lines of the two heads are shown respectively in full lines and dotted lines.

As shown in Figure 1, a magnetic recorder embodying the teachings and principles of the present invention includes a magnetic record member 10, such, for example, as a tape, having a non-magnetic base portion 11 and a magnetizable portion 12. By way of example and not by way of limitation, the base portion 11 may be in the form of a paper tape, while the layer of magnetizable material 12 may be in the form of powdered magnetizable material cemented or otherwise suitably secured as a coating to the tape base portion 11. The relative thicknesses of the base portion 11 and the coating of magnetic material 12 may vary through wide limits without departing from the spirit and scope of the present invention, and the coating 12 has been illustrated as being abnormally thick merely for the purposes of illustration to show that it is distinct from the base portion 11.

The magnetic record member 10 is arranged to pass between a pair of electromagnetic transducer heads 13 and 14. The head 13 includes a C-shaped core portion 15 forming confronting pole pieces having a non-magnetic gap 16 lying immediately above the record member 10. The head 13 is also provided with a signal coil 17 which is arranged to be energized with a fluctuating electric signal whose characteristics are to be recorded on the record member 10.

Similarly, the electromagnetic transducer head 14 includes a C-shaped core 18 having a non-magnetic gap 19 lying immediately under the record member 10. The head 14 is also provided with a signal coil 20 which is serially connected through the conductor 21 to the signal coil 17 of the head 13. The other ends of the coils 17 and 20 are connected through conductors 22 and 23 to any suitable energizing circuit or reproducing circuit.

As may be seen from an inspection of Figure 2 of the drawing, the positioning of the head 13 on top of the record member 10 and the head 14 on the undersurface of the record member 10 has the effect of placing the magnetizable layer of material 12 of the record member 10 immediately adjacent the ends or pole tips 24 and 25 of the head 13, but has the effect of spacing the pole tips 26 and 27 of the head 14 away from the layer of magnetizable material 12.

It has been found that when a magnetic record member in the form of a non-magnetizable base with a coating of magnetizable material thereon is caused to pass in contact with the poles of a mag-

netic head such as the magnetic head 13, all of the frequencies throughout the audio range are recorded on the record member, although the low frequency notes are not recorded at as high an energy level on the medium as are high frequency notes.

It has further been found that when a record member is passed over a head and the magnetizable coating maintained at a distance spaced from the pole tips such, for example, as spaced by a distance equal to the thickness of the paper tape forming the carrier for the magnetizable layer 12, only frequencies of under about 1,000 cycles are recorded. There is substantially no recording of the high frequency notes or middle frequency notes.

It has thus been found that by connecting a pair of electromagnetic transducer heads in series, such as the heads 13 and 14, and positioning one in contact with the magnetic layer 12 of magnetizable material and separating the head 14 therefrom by the thickness of the non-magnetizable carrier upon which the coating is carried, that a sufficient amount of base boost is obtained to counteract the reduced recording thereof by the head 13 when taken alone.

With an arrangement such as that shown in the drawing, it has been found that an extremely flat frequency response may be obtained throughout a wide frequency range including the low frequency range without resorting to an equalizer circuit or any separate circuit for introducing additional base energy into the electric circuit.

The arrangement may also be used for reproducing by connecting the conductors 22 and 23 to an output circuit rather than to an input circuit.

While I have shown a certain particular embodiment of my invention, it will, of course, be understood that I do not wish to be limited thereto, and I, therefore, contemplate by the appended claims to cover all such modifications as fall within the true spirit and scope of my invention.

I claim as my invention:

1. An electromagnetic transducing instrument comprising a magnetic record member having a non-magnetic base portion and a coating of mag-

netic material, and a pair of electromagnetic transducer heads electrically connected for joint operation, one of said heads being positioned in close proximity to the magnetic coating of said record member and the other of said heads being positioned in close proximity to the base portion of said record member, thereby to provide inherent base boost in said instrument.

2. An electromagnetic transducing instrument comprising an elongated magnetic record member having a base portion of non-magnetic material and a coating of magnetic material on one side only of said base portion, and a pair of electromagnetic transducer heads, each having confronting pole pieces spaced along the length of said medium, electrically connected for joint operation and disposed on opposite sides of said record member, one in contact with said magnetic material only and the other in contact with said base portion only.

3. An electromagnetic transducing instrument comprising an elongated magnetic record member having a base portion of non-magnetic material and a coating of magnetic material on one side only of said base portion, and a pair of electromagnetic transducer heads, each having confronting pole pieces spaced along the length of said medium, electrically connected for joint operation and disposed on opposite sides of said record member and in substantial contact therewith, said heads being located directly opposite each other in their respective positions on opposite sides of said record member with one in contact with said magnetic material only and the other in close proximity to the opposite side of said record member.
